UNITED STATES PATENT OFFICE.

WILLIAM G. COREY, OF SAN FRANCISCO, AND CHARLES A. TROW, OF COALINGA,
CALIFORNIA.

HYDRAULIC PUMPING POWER.

Application filed March 29, 1926. Serial No. 98,119.

Our invention relates to the art of pumping wells, and more particularly to a system for transmitting power from a central motor or engine to a plurality of wells for the simultaneous operation of their pumps. Such systems are known in the art as pumping powers, and commonly comprise a vertical shaft, rotated at a slow speed by the engine, and provided with a crank or eccentric from which cables or rods radiate outwardly to the various wells and are connected with the sucker rods thereof by suitable jacks, the operation of the crank or eccentric successively pulling and releasing the various cables or rods and thereby operating the well pumps.

The principal object of our present invention is to provide a pumping power in which the power is transmitted by fluid under pressure. A power driven pump is provided at a convenient location, and suitable conduits or pipe lines conduct the pressure fluid from said pump to the various wells, each of which is provided with a hydraulically operated jack for transmitting the power from the pressure fluid to the sucker rods of the well pump. The pressure or power fluid is contained in a closed system, as will be herein-after described, and is distributed from the central pump to the various well-pump jacks, by an automatically operated valve or switch mechanism, preferably in such a manner that the load on the driving motor or engine is constant.

By the use of our invention, we are able to reduce materially the operating and maintenance cost of a pumping power system. A small, high speed engine or motor, of maximum efficiency, can be used to drive the power pump, and there are no moving mechanical connections, such as cables or rods, which require frequent repair and adjustment. Moreover, the system may be used with wells of any depth, and with well-pumps of any desired length of stroke.

A further object of our invention is to provide, as a part of our pumping power system, a suitable jack or hydraulic engine for operating the well pump in such a manner that the movement of the sucker rod, at the ends of its stroke, is gradually arrested and reversed, without jar or sudden strain.

Other objects and advantages will become

apparent from the following description of a preferred embodiment of our invention, which should be read with the understanding that the form, proportion, and arrangement of the several parts may be varied, within the limits of the claims hereto appended, without departing from the spirit of the invention as set forth in said claims.

With this in view a preferred form of our invention will now be described fully with reference to the accompanying drawings, wherein—

Fig. 1 is a part sectional plan of the distributing valve and its connections.

Fig. 2 is a diagram, on a reduced scale, illustrating the general arrangement of our system.

Fig. 3 is a vertical section of one of the jacks for transmitting the power from the pressure fluid to the sucker rod of a well.

Fig. 4 is a transverse section taken on the line 4—4 of Fig. 3.

Referring first to the diagram shown in Fig. 2, the reference numeral 1 indicates the power pump, which is understood to be operated continuously by any suitable motor or engine, not shown. 2 is the intake and 3 is the discharge of said pump. 2' and 3' are manifolds respectively connecting said intake and discharge with a distributing valve or hydraulic switch indicated at 4.

5 is a pipe line leading from the valve 4 to the jacks for operating the pumps of the wells indicated at 6, and 7 is a similar pipe line from said valve to the jacks of the wells 8.

It will be seen that the wells and their jacks are divided into two groups, 6 and 8. 90 The valve 4 is so operated that the high-pressure fluid delivered by the pump discharge 3 is alternately supplied to said two groups, and the spent or low-pressure fluid is alternately returned therefrom to the pump intake 2. Thus during one-half of the cycle, the pump 1 delivers fluid under pressure to the jacks of the wells 6, for example, and draws spent fluid from the jacks of the wells 8. During this period, the pump 100 plungers of the wells 6 are lifting, on their working stroke, and the pump plungers of the wells 8 are lowering, by gravity, on their return stroke. Then during the next half-cycle, the reverse operation takes place, the power pump 1 drawing spent fluid from the

jacks of the wells 6 and delivering it under pressure to the jacks of the wells 8, thus completing the cycle.

It should be noted that the power fluid is circulated in a closed system, and has no connection with the well fluid. The power fluid may be of any suitable nature, but is preferably a liquid. It should also be noted that the number of wells pumped by one power may be varied to suit the particular local conditions, and that the number of jacks in each group may also be varied. The aggregate capacity of the jacks in one group should be approximately equal to the aggregate capacity of those in the other group, however. It is entirely possible, moreover, to operate more than two groups of jacks from one power pump.

Turning now to Fig. 1 of the drawings, the valve 4 comprises a pair of aligned cylinders 9 and 9', in which operate pistons 10 and 10', and said pistons are connected together by a rod 11. In its central region, said rod carries a piston 12, which operates in a cylinder 13. Stops 14, comprising fixed sleeves surrounding the rod 11, are provided for limiting the travel of said rod and its pistons. The cylinders 9, 13 and 9' are connected together by suitable spacing frames 15, and are provided with suitable packing glands indicated at 16.

The cylinders 9 and 9' are respectively provided with ports 17 and 17', which lead into surrounding chambers 18 and 18'. The pipe lines 5 and 7, leading to the two groups of jacks, terminate, respectively, in the chambers 18 and 18'. The pump intake manifold 2' connects with the outer ends of the cylinders 9 and 9', and the discharge manifold 3' connects with their inner ends. Said discharge manifold also has branches 19 and 19' leading respectively to the chambers 18 and 18', and said branches are provided with check valves 20 and 20', which permit the fluid to pass, as indicated by the broken arrows, from the chambers 18 and 18' back into the manifold 3' if, in certain portions of the cycle, the pressure in said chambers 18 and 18' rises above that in said manifold 3'. The manifold 2' is also provided with check valves 21, which permit flow only in the direction of the broken arrows, i. e. toward the pump intake 2. Said manifold 2' is preferably provided, also with air compression chambers, indicated at 22.

The central cylinder 13 is the operating cylinder for the valve rod 11. Its ends are respectively connected with the pipe lines 5 and 7 by pipes 23 and 23', in which are adjustable pressure-actuated relief valves 24 and 24'. By-passes 25 and 25' are provided around said relief valves, and said by-passes have check valves 26 and 26' which permit flow only in the direction indicated.

The operation of the valve is as follows:—

Assuming the pump 1 to be operating continuously, and the movable valve parts 10, 10' and 11 to be in the position shown, i. e. at the left hand limit of their travel, high-pressure fluid will flow from the pump 1 through the left hand portion of the manifold 3', the valve cylinder 9', the ports 17', the chamber 18', and the pipe line 7 to the group of well pump jacks connected therewith, causing said jacks to raise their respective well pump plungers. At the same time, spent or low-pressure fluid will return from the other group of jacks (which are lowering their pump plungers) through the pipe line 5, the chamber 18, ports 17, valve cylinder 9, and the right hand branch of the manifold 2' to the pump 1.

When the jacks connected with the pipe line 7 complete their power strokes, the pressure in said pipe line rises above the normal working pressure, and causes fluid to flow through the pipe 23' and the relief valve 24', (which is set to open only at such increased pressure) into the left hand end of the cylinder 13. This shifts the valve 10 to the right, the fluid from the right hand end of said cylinder 13 flowing out through the by-pass 25 and the check valve 26. The conditions are now exactly reversed from those described above, so that high-pressure fluid flows out through the pipe line 5, raising its jacks, and low-pressure or spent fluid returns through the pipe line 7 from its jacks. At the end of the power stroke of the jacks on the pipe line 5, the increasing pressure causes fluid to flow through the pipe 23 and the relief valve 24, thereby shifting the valve again to the left, whereupon a new cycle begins. The operation of the valve is therefore automatic, and is caused by the increasing pressure in the high-pressure line at the end of the power stroke of the jacks connected therewith. It will be seen from Fig. 1 that the fluid pressure upon the valve pistons 10 and 10' is balanced at all times, the inner faces of said pistons being exposed to the high pressure fluid in the manifold 3' and their outer faces exposed to the low pressure fluid in the manifold 2'. The valve, therefore, remains in either of its two positions until the pressure upon the actuating piston 12 is reversed.

We have shown, in Figs. 3 and 4, a preferred form of jack for use as a part of our pumping power system. 27 is a vertical tubular supporting member which is rigidly attached, as, for example, by a flange 28 and bolts 29 as shown in Fig. 4, to the casing-head (not shown) of the well. The lower end of said member has slots 30, in which operates a vertically movable cross-head 31 secured to the upper end of the sucker rod string 32, Fig. 3. A separable connection between the cross-head and said sucker rods 130

may be made by means of an elongated slot 33, Fig 4, in said cross-head, and a correspondingly shaped head 34 secured to said sucker rods and turned normally at right angles to said slot, as shown.

The cross-head 31 is connected by rods 35, Fig 3, with an upper head 36, which is secured to the upper end of a piston or plunger 37, and said plunger operates in a cylinder 38 carried by the upper end of the supporting tube 27. Suitable packing is provided at 39, and a suitable guide 40, through which the side rods 35 operate, is secured to the cylinder 38.

Fluid from the pipe line enters at 41, Fig. 3, into a valve chamber 42 supported within the tube 27, and passes up through two spaced valve ports 43 and 43' into the cylinder 38. The ports 43 and 43' are closed, 20 at the ends of the stroke of the plungers 37, by respective conical valve plugs 44 and 44', which are carried respectively by a rod 45 and a sleeve 45' secured to and extending downwardly from the plunger head 36. In 25 the position shown in Fig. 3, in which the plunger is at the upper end of its stroke, the port 43' is closed by the valve plug 44', as shown, thus cutting off the supply of fluid to the cylinder 39. Similarly, at the lower 30 end of the stroke, the port 43 is closed by its valve plug 44, thereby preventing further escape of fluid back into the pipe line.

The valve plugs 44 and 44' are conical, as shown, to effect a gradual closing of the 35 ports 43 and 43', so that the motion of the plunger will be arrested without jar when the operating fluid is a liquid, and so that the pressure in the pipe line will not be increased too suddenly upon the closing of the 40 upper valve. The plugs 44 and 44' are slideable upon their respective supports 45 and 45', to enable fluid to pass them at the beginning of each stroke, before the plunger begins to move. The lower plug 44 is held 45 in its normal position, against the nuts 46, by its own weight, and the upper plug 44' is supported upon a spring 46'. The valve plug supports 45 and 45' are adjustably and frictionally held in the plunger head 36 by 50 means of clamping collars 47 and 47', and packing 48 and 48', respectively, so that the position of the plugs can be properly set with relation to the length of the stroke. This construction also prevents undue strain 55 upon the valve plugs or their supports in case of leakage of fluid past said plugs, the supports sliding through the plunger head until the latter comes to rest. The plunger 37 is preferably hollow, as shown, and is 60 provided with an inner tubular member 49 surrounding the plug supporting sleeve 45' and secured permanently to the head 36. A compression chamber is thus provided 65 between said sleeve and the outer wall of the plunger.

The operation of the system as a whole will now be understood clearly. Assuming the pump 1 to be running continuously, the high-pressure fluid is first diverted, say to the pipe line 7, by the distributing valve 4, 70 and is conveyed by said pipe line to the jacks at the wells 8, Fig. 2. At each such jack, the fluid enters at 41, Fig. 3, and, passing through the ports 43 and 43' into the cylinder 38, elevates the plunger 37, thereby 75 lifting the sucker rod 32 and operating the well pump, not shown, upon its working stroke. When the plungers of all the jacks on the line 7 reach the upper ends of their respective strokes, their valve plugs 44' close 80 their ports 43', thus shutting off all outlet from the line 7. The pressure in said line thereupon rises above the normal, thereby causing fluid to pass through the relief valve 24', Fig. 1, into the valve operating cylinder 85 13, and to shift the distributing valve to its opposite position. The high-pressure fluid now passes from the pump 1 into the pipe line 5, and thence to the jacks at the wells 6, Fig. 2, causing them to elevate their sucker rods as described above. At the same time, the spent or low-pressure fluid from the jacks at the wells 8 returns through the line 7 and the valve 4 to the pump, the plungers of said jacks being caused to descend by the 90 weight of the sucker rods attached thereto. This cycle is repeated automatically as long as the pump 1 is operated.

It is to be understood that the above described means for operating the distributing valve 4 directly by the increasing pressure occurring at the ends of the strokes of the jack plungers is merely a convenient example. The same result may be accomplished by any other suitable means, which will shift the distributing valve, or cause it to be shifted, upon the completion of the strokes of the jack plungers. The essential principle involved is that the distributing valve is controlled by the movement of the jack plungers, and we wish it understood that our invention, as defined in the claims hereunto appended, includes any suitable valve controlling means operating under said principle.

We claim:—

1. In an apparatus for the described purpose, means adapted to supply fluid under pressure; a fluid pressure actuated motor device comprising a cylinder and a plunger operable therein; a conduit connecting said device with said fluid supply means; a valve controlled by said device for cutting off its communication with said conduit; and means controlled by the rise in pressure of the fluid in said conduit caused by the closing of said valve for cutting off the supply of fluid from said supply means to said conduit.

2. In an apparatus for the described purpose, means adapted to supply fluid under

- pressure; a fluid actuated motor device comprising a cylinder and a plunger operable therein; a conduit connecting said fluid supply means with said cylinder; a valve seat member in said conduit; a valve stem frictionally held in said plunger for relative movement in the direction of travel thereof; and a valve carried by said stem and adapted to coact with said seat member to close said conduit to the passage of fluid in one direction, said valve being movable upon said stem to permit the passage of fluid in the other direction.
3. In an apparatus for the described purpose, means for supplying fluid under pressure; a working cylinder; a plunger operable therein; a valve chamber member positioned at one end of said cylinder and provided with a pair of spaced aligned valve seats; a conduit connecting said fluid supply means with the end of said chamber remote from said cylinder; a pair of valve stems frictionally held in said plunger for relative movement in the direction of travel thereof and extending
- into said chamber; and a valve carried by each stem, said valves being adapted to coact respectively with said seats to close the communication between said conduit and said cylinder at each end of the travel of said plunger.
4. An apparatus for the described purpose comprising means for supplying fluid under continuous pressure; a plurality of working cylinders; a reciprocating plunger in each cylinder; means for distributing the pressure fluid successively to said cylinders to operate said plungers; a conduit connecting each cylinder with said distributing means; a valve operated by each plunger at the end of its stroke for closing the conduit leading to its cylinder; and means actuated by the rise in the pressure of the fluid caused by the closing of said valves for operating said distributing means.

In testimony whereof we have signed our names to this specification.

WILLIAM G. COREY.
CHARLES A. TROW.
